UNITED STATES PATENT OFFICE.

JOHN E. DONOVAN, OF CINCINNATI, OHIO.

VAPOR-BURNER.

SPECIFICATION forming part of Letters Patent No. 469,443, dated February 23, 1892.

Application filed October 4, 1886. Serial No. 215,236. (No model.)

To all whom it may concern:

Be it known that I, JOHN E. DONOVAN, a citizen of the United States, and a resident of Cincinnati, in the county of Hamilton and State of Ohio, have invented certain new and useful Improvements in Vapor-Burners, of which the following is a specification.

This invention is an improved vapor-burner. Its object is to supply the burner with gas completely vaporized and mingled with the requisite quantity of atmospheric air to insure a perfectly blue smokeless flame of large volume and at the same time retain complete control of the volume of flame, whereby I am enabled to reduce the volume to any extent required without extinguishing the flame.

Its object is also to remedy the trouble heretofore existing in some of this class of burners which causes the pulsation of the flame.

These objects I accomplish by the means hereinafter described, whereby the gaseous vapor is supplied in a highly-heated state to the commingling-chamber unmixed with any of the liquid from which the gas is formed.

The invention also consists in the peculiar combination and arrangement of the several parts to accomplish these results, all of which will be first fully described in connection with the accompanying drawings, and then particularly referred to and pointed out in the claims.

Referring to the drawings, in which like parts are represented by similar reference-letters wherever they occur throughout the various views, Figure 1 is a central vertical section of my improved burner and its attachments. Fig. 2 is a top plan view of the same. Fig. 3 is a detail sectional view, upon an enlarged scale, of the supply and discharge tubes shown at the right-hand side of Fig. 1. Fig. 4 is an inverted perspective view of the detachable burner-cap.

The pipe leading from the reservoir is represented by A. It connects with the union B, the branch b of which is screw-tapped to receive the spindle C of the ordinary needle-valve. Into the vertical portion b' of the union is screwed the tube D, the lower end of the tube extending downwardly within the union to a point above the needle-valve, the

end of the tube and the screw-threaded plug upon the cross-head E forming a chamber b², surrounding the intermediate tube F, which passes within the tube D and rests upon the end of the screw-plug e, which closes the end of the union b'. Within the tube F is an inner tube G, which I term the "vapor-supply tube," which is screw-tapped into the end of the screw-plug e. H is the vaporizing-chamber. It has boss h extending down from its under side, into which is screwed the top end of the tube D. The intermediate tube F extends up into this boss, preferably a short distance above the end of tube D, while the inner tube G extends to the top of the circular chamber H and has slots or U-shaped depressions around its top edge to permit the vapor to pass from the chamber H down through the tube G, through a perforation in the plug e, and thence through a perforation in the cross-head E to the discharge-orifice in the vertical portion E' of the cross-head. The opening in the upper portion of this vertical part E' is closed by a needle-valve on the upper end of the spindle I, which is screw-threaded through the vertical portion E' and controlled by a hand-wheel I'. The commingling-chamber is formed by the under side of the vaporizing-chamber H and the circular dish-shaped casting J, which has a tube J, cast with it, extending down in proximity to the vapor-discharge orifice e' and up above the bottom of the casting J and within the detachable burner-cap K. The upper portion of the casting J is perforated with a row of jets j, and the cap K is similarly perforated with a circular row of jets k. This cap K passes over the extended end of the tube J' and rests upon an annular flange h', projecting inwardly from the chamber H. The piece J has a boss j' extending down from it, which is perforated to pass over the tube D and is tapped to receive a set-screw J², which holds it firmly in place against the exterior annular flange h², surrounding the chamber H. The bosses h³, of which there are four extending out from the chamber H, furnish openings through which the core-bearings pass in casting the chamber in a single piece. The bosses are screw-tapped and stopped with screw-plugs h⁴. L is the ordinary oil-cup, in which

oil is ignited to initiate the vaporizing process. The lower end of the intermediate tube F, which is within the chamber b^2 , is perforated to permit the fluid from the supply tank to pass between the tubes F and G, as well as between the tubes D and F, on its way to the vaporizing-chamber H. The fluid passes from the reservoir (not shown) through pipe A, and thence up into the lower part 10 of chamber H, a portion of the fluid passing between tubes D and F and a portion passing between the tubes F and G. The vaporized fluid which arises within the chamber H is forced by the pressure generated by the vaporizing process down through the tube G and delivered from the perforation e' into the tube J', carrying along with it the requisite amount of atmospheric air, and thence into the commingling-chamber J ^{3} , formed by the parts 15 H, J, and K. The vapor passes out through the perforations j and k , and being ignited burns with a perfectly smokeless blue flame. The flames from jets k , impinge upon the upper surface or top of the chamber H, heating it 20 intensely. The chamber is also heated upon the under side by the highly-heated vapor in the commingling-chamber J ^{3} . The heated vapor passing down through the tube G partially heats the fluid passing up around it to 25 the chamber H, and the fluid between the tubes G and F and F and D, being in communication above and below tube D, equalizes the pressure and prevents the pulsations of the flame so annoying in the burners now in 30 common use, because the fluid thus entering between the tubes is particularly heated and expanded before it reaches the bottom of the vaporizing-chamber. The process of vaporization is therefore gradual from the time 35 40 the fluid enters the vertical branch b' of union B until the perfectly-vaporized fluid

from the top of chamber H, is forced into the tube G and thence discharged in a constant steady stream from nipple e through tube J' to the commingling-chamber, while the intermediate tube F, perforated below, prevents the formation of paraffine and insures a more perfect vaporization of the fluid discharged through the jets j and k . This tube F is not indispensable in my organization, as the device will accomplish good results without it. The section of pipe A' (shown in Fig. 2) is a continuation of the tube A to be used when more than one burner is to be employed in the same stove. 45 50

What I claim as new, and desire to secure by Letters Patent, is—

1. In a vapor-burner, the combination, substantially as specified, of the vaporizing-chamber H, the burner surrounded by said chamber, the fluid-supply tube D, leading to the bottom of said chamber, and the vapor-discharge tube G within said tube D in communication with the top of said chamber. 60

2. The combination, substantially as specified, of the vaporizing-chamber, the supply-tubes D and F, leading to the bottom of said chamber, and the vapor-discharge tube leading from the top of said chamber, the said tube F being intermediate the tubes G and D and perforated near the bottom, for the purpose set forth. 65 70

3. The combination, substantially as specified, of the chamber H, having flanges h' h^2 , the dish J having its upper edge bearing against flange h^2 , the tube J', and detachable cap K, said cap and part J being perforated as described, for the purpose set forth. 75
